UNITED STATES PATENT OFFICE.

HARRY W. PUGH, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SUBSTATION APPARATUS.

1,406,223.

Specification of Letters Patent. Patented Feb. 14, 1922.

Application filed October 30, 1919. Serial No. 334,454.

To all whom it may concern:

Be it known that I, HARRY W. PUGH, a citizen of the United States, residing at New York, in the county of Bronx, State of New York, have invented certain new and useful Improvements in Telephone Substation Apparatus, of which the following is a full, clear, concise, and exact description.

The invention relates to telephone substation apparatus and more particularly to substation apparatus particularly adapted for use in connection with toll or measured service in automatic telephone exchange systems.

Apparatus of this character involves, in addition to the usual transmitter, receiver and call bell, mechanism for evaluating or measuring the telephonic service furnished at a substation and mechanism for controlling the automatic switches utilized in establishing telephonic connection. The service measuring or evaluating mechanism may take the form either of a message register or counter, or a coin-handling mechanism designed to collect coins in payment for the service furnished. The mechanism for controlling the automatic switches usually takes the form of the well-known impulse sender of calling dial.

The invention contemplates a very compact and convenient arrangement of apparatus at a substation for performing the functions above outlined, and an apparatus which in addition to its compactness and convenience is constructed to prevent tampering with the service-evaluating mechanism.

In accordance with the invention, the service-evaluating mechanism is inclosed in a substantial casing in order to prevent unauthorized access thereto; and the impulse-sending mechanism is mounted on the exterior of the casing to permit the operation thereof by the subscriber.

The mounting of the impulse-sending mechanism on the exterior of the casing involves an aperture or apertures in the casing; first for the attachment of screws or bolts, and also to permit the electrical connection of the contact springs of the impulse-sending mechanism in operative relation with the rest of the substation mechanism which is included within the casing. The invention, however, provides means for preventing access to the service-evaluating mechanism through the aperture occasioned by the mounting on the casing of the im-

pulse-sending mechanism. This means in one embodiment of the invention takes the form of a shield which is interposed between the aperture or apertures in the casing and the service-evaluating mechanism.

It is desirable both for the convenience of the user and convenience in making the necessary adjustments to the impulse-sending mechanism that it be mounted in a position on the casing where it will be on or about the level of the eyes of the telephone user. The invention, therefore, contemplates the mounting of the impulse-sending mechanism on the casing just above the transmitter, which, as is usual, is mounted at about the level of the mouth of the average user. Since the impulse-sending mechanism involves the rather complex governor and set of contact springs, in accordance with the invention it is so mounted that this part of the mechanism extends within the casing so that the shield which prevents unauthorized access to the service-evaluating mechanism serves another useful purpose, especially where the service-evaluating mechanism is the usual coin-collecting mechanism, in that it prevents coins thrown out of the coin chute of the coin-collecting mechanism from impinging on and interfering with the operation of the mechanism of the impulse-sending device.

In the drawing, Figs. 1 and 2 are the side and front elevations respectively, partially in section, of so much of a substation apparatus as is necessary for the understanding of the present invention. In the embodiment of the invention illustrated in the drawings, the service-evaluating mechanism is in the form of a coin collector and may be in all respects similar to that disclosed in Patent #1,043,219 to O. F. Forsberg, granted November 5, 1912. The impulse-sending mechanism, although it may be of any usual construction, is as shown on the drawing, 100 similar to that disclosed in Patent #1,161,854 to O. F. Forsberg, granted November 30, 1915. For the sake of clearness, the major portion of the complicated coin-handling mechanism is omitted from the drawing. 105 This mechanism which may be that of the Forsberg patent above-mentioned, is with the exception of the coin chute, mounted upon the base 1 and is entirely enclosed in a heavy sheet metal casing 4, from the upper 110 wall of which is supported the coin chute 13 extending within the casing. The usual

coin-receiving guide 5 is mounted on the exterior of the casing opposite the upper end of the coin chute. Mounted in an aperture 9 in the front of the casing is the impulse-
 5 sending mechanism 10 which is provided with the usual governor shown at 12, and contact springs 11 projecting within the casing. As clearly indicated in Fig. 2 this mechanism is mounted above and in vertical alignment with the transmitter 2, which is supported from a bracket 8 also mounted on the exterior of the casing. The receiver 26 is supported from the usual hook switch 25, which is also carried by the base 1. The
 10 coin chute 13 is provided with a number of apertures, one of which is indicated at 6, which apertures are so proportioned and arranged that spurious or undersized coins in passing down the coin chute are automatically ejected from the chute by gravity. These rejected coins are prevented from striking the contact springs 11 or other mechanism of the impulse-sending mechanism by means of a shield 14 which is supported from the upper wall of the casing 4. The side of the shield adjacent the coin chute is provided with a facing 15 which may be of cloth or felt. Inasmuch as the impulse-sending mechanism 10 requires frequent adjustment, it is very advantageous to mount it so that it may be removed for adjustment or replacement. However, in order to prevent dishonest persons from obtaining access to the coin-handling mechanism for the
 25 purpose of manipulating it to their advantage by removing the impulse-sending mechanism or a portion thereof, the shield 14 is so formed that, together with the guides 16 and 17 which ordinarily guide the rejected coins to the refund point, it substantially encloses or shields the coin-handling mechanism.

The contact springs 11 controlled by the impulse-sending device, are connected by a
 40 cord 18 including four conductors to the contact springs 20^a, 20^b, 20^c and 20^d, which are mounted on a bracket 22 secured to the inner wall of the casing 4. The free ends of these contact springs make electrical contact
 45 with corresponding contacts 23^a, 23^b, 23^c and 23^d mounted on the block 24 which is supported by the base 1, when the casing 4 is in place on the base 1. This arrangement permits the removal of the casing without disturbing the permanent electrical connections to the impulse-sending device. As shown in the drawings the contacts 23^a, 23^b, 23^c and 23^d are of different lengths and heights and consequently each engages a different one of the contact springs 20^a, 20^b, 20^c and 20^d, which are arranged in pairs in stepped relation.

What is claimed is:

1. A telephone set comprising a casing, a
 60 coin handling mechanism within said cas-

ing, a transmitter and receiver supported without said casing, an impulse-sending device mounted to partially extend within said casing and a shield interposed between said coin mechanism and said impulse sender. 70

2. A telephone set comprising a casing, a coin-handling mechanism enclosed therein, a transmitter, a receiver, an impulse-sending device mounted within an aperture in said casing, and a shield juxtaposed to said aperture to prevent unauthorized access to said coin-handling mechanism through said aperture. 75

3. A telephone set comprising a casing, coin-handling mechanism enclosed therein including means to collect and to reject coins, an impulse-sending mechanism having a portion extending within said casing and a shield interposed between said coin-handling mechanism and said casing to prevent coins rejected by said coin-handling mechanism from interfering with said impulse-sending mechanism. 80

4. Telephone substation apparatus comprising a casing provided with an aperture, a coin-handling mechanism enclosed therein, an impulse-sending device mounted on the exterior of said casing, electrical terminals for said sending device mounted within said casing and accessible for electrical connection with said sending device through an aperture in said casing and means for preventing unauthorized access to said coin-handling mechanism through said aperture. 90

5. Telephone substation apparatus comprising a casing provided with an aperture, a coin-handling mechanism enclosed therein, an impulse-sending device mounted on the exterior of said casing, electrical terminals for said sending device mounted within said casing and accessible for electrical connection with said sending device through an aperture in said casing, and a shield interposed between said coin handling mechanism and said casing to prevent coins rejected by said coin-handling mechanism from interfering with said impulse-sending mechanism. 100

6. Telephone substation apparatus comprising a base, a coin-handling mechanism mounted on said base, a casing therefor supported from said base, an impulse - sending device and electrical terminals therefor mounted on said casing, cooperating terminals mounted on said base to make contact with the terminals on the casing when the said casing is in place on the base, and a shield interposed between said coin-handling mechanism and said casing to prevent coins rejected by said coin-handling mechanism from interfering with said impulse-sending device. 110

In witness whereof I hereunto subscribe my name this 27th day of October, A. D. 1919.

HARRY W. PUGH.
